CLAIM

The ornamental design for a display screen or portion thereof with graphical user interface as shown and described.

DESCRIPTION

The file of this patent contains at least one drawing executed in color. Copies of this patent with color drawings will be provided by the Office upon request and payment of the necessary fee.

The sole FIGURE is a front view of a display screen or portion thereof with graphical user interface showing my new design.

The outer peripheral broken lines illustrate a display screen or portion thereof and forms no part of the claimed design.

**1 Claim, 1 Drawing Sheet
